UNITED STATES PATENT OFFICE.

JOSEPH DUFRESNE, OF MONTREAL, QUEBEC, CANADA.

SHUTTLE-THREADER.

1,093,837.

Specification of Letters Patent. Patented Apr. 21, 1914.

Application filed November 26, 1913. Serial No. 803,320.

To all whom it may concern:

Be it known that I, JOSEPH DUFRESNE, a citizen of the United States, and residing at 82 Turgeon street, Montreal, Province 5 of Quebec, Canada, have invented certain new and useful Improvements in Shuttle-Threaders; and I do hereby declare that the following is a full, clear, and exact description of the invention, such as will enable 10 others skilled in the art to which it appertains to make and use the same.

The invention to be hereinafter described relates to threader for shuttles.

In order to more clearly disclose the construction, operation, and use of the invention, reference should be had to the accompanying drawings forming part of the present application.

Throughout the several figures of the 20 drawings like reference characters designate the same parts.

In the drawings: Figure 1 is a plan view of the device as used; Fig. 2 is an end view of the same; Fig. 3 is a fragmentary, 25 tail, plan view of the thread end of the shuttle; Fig. 4 is a section on line 4—4 of Fig. 3 looking in the direction of the arrows; and Fig. 5 is a detail of the mounting of the threading needle.

The main objects of the invention are, to 30 provide neat, compact, durable, and efficient, mechanical means, for threading shuttles, quickly and accurately; such means being capable of being produced at a relatively 35 low cost.

Referring to the drawings in detail, 1 designates the shuttle of usual construction, provided at one end with a small tube 2 set therein at a considerable angle; and provided 40 at its center with a slot 3, which is centrally located in a depression 4 of the shuttle. The depression 4 communicates with the central opening of the shuttle by a channel 5 and is provided with a narrow 45 contiguous groove 6 extending nearly to the end of the bobbin; for a purpose to be later disclosed. The shuttle 1 is secured in a boxing 7 by means of slidably adjustable holding blocks 8, directed to receive the 50 ends of the shuttle, and slidably operative on the lower side of boxing 7 by bolt and nut means 9 operative through suitable slots therein. Boxing 7 is obliquely slidable on slanting plates 10 which are secured to the 55 base board 11. Suitable bolts 12 in the base of the boxing coöperate with grooves 13

in the board 11 to guide the boxing 7 as well as limit its movement, and secure it in position. The boxing 7 is normally held in raised position by the action of a tension 60 spring 14, the upper end of which is secured to the base board 11 and the lower end of which is secured to the outer end of the more centrally located bolt 12; as in Fig. 1. To one side of the boxing 7, near the right 65 hand end thereof, there is pivotally secured a curved finger 15, operative through a suitable slotted guiding plate 16, fixedly secured to the boxing. The finger 15 is provided with a lower cam portion 17 and a 70 projecting shoulder 18, which coöperates with an adjustable standard 19 secured to the base plate 11, to limit the outward rotation of the finger. A tension spring 20 secured to the finger below its pivotal point 75 and to the side of the boxing, acts to normally keep the finger raised; as in Fig. 2. Near the standard 19 a needle post 21 is provided. The post 21 carries a threading needle 22 which lies in the same plane as 80 tube 2 and is inserted part way into a bore in the side of the boxing, alined with the end of the tube; as in Fig. 1.

The operation is as follows: The shuttle is placed between the blocks 8 so that the bore 85 in the side of the boxing is alined with the tube 2. The thread from the shuttle is then laid along channel 5, across the slot 3 of tube 2, along slot 6, and through the slot 6^a of block 8. Boxing 7 is then pushed downwardly, against the action of spring 14. This forces the cam portion 17 of finger 15 against standard 19, so as to rotate the finger 90 downwardly and inwardly; as will be evident from Fig. 2. The finger, as it is forced 95 downwardly engages the thread just in front of the slot 3 and forces it thereinto. When the finger has reached this position the lower shoulder of the cam portion 17 has reached the top of the standard, and travels there- 100 along, without further rotating the finger, as will be evident; so that now the finger simply acts to hold the thread pressed firmly into the slot 3. By forcing the box 7 down still farther the outwardly presented hook 23 105 of needle 22 is forced in back of the thread. When the box is released it is drawn upwardly by spring 14 and the needle engages the thread, which is still held taut by finger 15, so as to draw it through tube 2, and thus 110 thread the shuttle. As the box returns to its original position the finger 15 will be

returned to its original position also, by spring 20, so as to be ready for another threading.

This device may be bolted to any suitable 5 bracket or standard, on the machine, near the operator, so as to be always available for use.

It is thought that the construction, operation, and use of the invention will be clear 10 from the preceding detailed description.

Changes may be made in the construction, arrangement, and disposition of the several parts of the invention without in any way departing from the field and scope of the 15 same, and it is meant to include all such within this application wherein only a preferred form has been disclosed.

Having thus fully described my invention, what I claim as new and desire to secure by 20

Letters Patent is:

In a device of the character described; a base plate; a box, obliquely slidable thereon; means for securing the box to the base plate and for limiting and controlling its movement; slidably adjustable shuttle holding 25

means contained within the box; a shuttle carried thereby, and provided near one end with a horizontal, centrally slotted, and angularly disposed tube, one end of which is aligned with a bore in one side of the box; a standard secured to the base plate, contiguous to one side of the box and near one end thereof; a threading needle mounted in the standard in alignment with the tube and in the same plane therewith; a pivotally mounted cam, thread depressing means, mounted on the side of the box and adapted to depress the thread across the slot in the tube; guiding means therefor; means for depressing the thread depressing means as the box is depressed; means for returning the thread depressing means to its original position; and means for returning the box to its original position.

In witness whereof I have hereunto set my hand in the presence of two witnesses.

JOSEPH DUFRESNE.
